(57) **CLAIM**

The ornamental design for a ceiling fan dusting tool, as shown and described.

DESCRIPTION

FIG. 1 is a top rear perspective view of a ceiling fan dusting tool according to the present disclosure;
FIG. 2 is a first side view of the ceiling fan dusting tool of FIG. 1, the opposite side being identical thereto;
FIG. 3 is a top plan view of the ceiling fan dusting tool of FIG. 1;

FIG. 4 is a bottom view of the ceiling fan dusting tool of FIG. 1;

FIG. 5 is a first end plan view of the ceiling fan dusting tool of FIG. 1; and,

FIG. 6 is a second end plan view of the ceiling fan dusting tool of FIG. 1.

The broken line showing is included for the purpose of illustrating and forms no part of the claimed design.

1 Claim, 4 Drawing Sheets
